CLAIM

The ornamental design for a sensor for golf, as shown and described.

DESCRIPTION

FIG. 1 is a front perspective view of a sensor for golf according to the present design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view thereof;

FIG. 9 is a rear-bottom perspective view thereof; and,

FIG. 10 is a view showing the usage state thereof.

The broken lines showing of parts of the drawing are for the purpose of illustrating use and form no part of the claimed design.

1 Claim, 9 Drawing Sheets
